(57) **CLAIM**

The ornamental design for a product display kiosk, as shown.

DESCRIPTION

The kiosk is intended as a retail point of sale display kiosk to display articles for sale by stacking or hanging them to allow the articles to be selected and removed for purchase. FIG. 1 is a front perspective view of a kiosk showing my new design;

FIG. 2 is a back view thereof; and,

FIG. 3 is a side view thereof.

1 Claim, 2 Drawing Sheets

FIG. 1

FIG. 3

FIG. 2
